UNITED STATES PATENT OFFICE.

HENRY F. SHAW, OF BOSTON, AND GEORGE F. SHAW, OF DEDHAM, MASSACHUSETTS, ASSIGNORS OF ONE-FOURTH TO HARRY L. AYER, OF BOSTON, MASSACHUSETTS.

CAR-WHEEL.

SPECIFICATION forming part of Letters Patent No. 634,036, dated October 3, 1899.

Application filed October 29, 1898. Serial No. 694,966. (No model.)

To all whom it may concern:

Be it known that we, HENRY F. SHAW, of Boston, in the county of Suffolk, and GEORGE F. SHAW, of Dedham, in the county of Norfolk, State of Massachusetts, have invented 5 certain new and useful Improvements in Car-Wheels, of which the following is a specification.

This invention has for its object to provide 10 a wheel adapted particularly for street-railway cars, which shall be adapted to travel on curves with the minimum frictional wear and resistance.

The invention consists in the improvements 15 which we will now proceed to describe and claim.

Of the accompanying drawings, forming a part of this specification, Figure 1 represents 20 an edge view of a pair of car-wheels embodying our invention, the track on which said wheels rest being shown in section. Fig. 2 represents a section on line 2 2 of Fig. 1, showing portions of the wheels above said line in dotted lines. Fig. 3 represents an enlarged 25 section on the line 3 3 of Fig. 1. Fig. 4 represents a view similar to Fig. 3, showing the ordinary form of car-wheel flange.

The same letters of reference indicate the same parts in all the figures.

30 In one of the ordinary forms of car-wheels the outer face of the flange or that face which bears against the side face of the rail is usually formed at an approximate right angle with the tread-surface of the wheel, as shown 35 in Fig. 4. When the wheel is running on a curve, the portion of the flange which projects below the tread-surface of the rail and bears against the adjacent side of the rail does not conform to the outline of the said adjacent 40 side and bears thereon only at its extreme end portions. The result is a grinding contact between the end portions of this part of the flange and the side surface of the rail and a rapid wearing away of both parts. In con- 45 sequence of this fact it is now common to equip street-cars with so-called "radial" trucks having provisions for keeping the portions of the flanges that project below the tread-surfaces of the rails as nearly parallel 50 with the sides of the rails as possible, these

arrangements being more or less complicated and expensive.

Our invention has for its object to overcome the grinding and wearing tendency above referred to and to enable the flanges of car-wheels to run, whether mounted on radial trucks or not, with the minimum frictional wear on the side surfaces of the rails. To this end we provide the flange of each wheel with a beveled face *a*, which stands at an angle of approximately forty-five degrees with the tread-surface *b* of the wheel, so that the portion of the flange that projects below the tread-surface *c* of the rail will present to the inner edge *c'* of the rail a curved surface 60 which for a considerable portion of its length is approximately parallel with the edge *c'* of the rail, as shown in Fig. 2, and therefore has an elongated bearing thereon, so that the wear of the wheel and rail due to the passage 65 of the wheel over curves in the track is materially reduced, and the frictional resistance is so far reduced that the boxes in which the axles are mounted may be, if desired, fixed rigidly to the trucks without provision for 70 adjustment such as that provided by the so-called "radial" truck. We prefer to curve the inner portion of the face *a* inwardly to the point where it joins the tread-surface *b* of the wheel to form a shoulder *a'*, surround- 75 ing the tread-surface and preventing tendency of the flange to slip upwardly on the rail, which might exist if the beveled surface *a* were continued without being thus curved inwardly to the tread-surface *b*. The face is 80 curved inwardly to a slight extent between its outer and inner edges, as shown in Fig. 3, this curvature giving the portion of the face that projects below the tread-surface of the rail a somewhat longer bearing on the edge 85 *c'* of the rail.

The portion of the flange forming the shoulder *a'* is substantially at a right angle to the tread-surface *b* of the wheel and engages the inner side of the rail close to the top or tread 90 surface thereof and prevents the flange from riding up on the rail. As the said shoulder is slight, however, it does not materially interfere with the engagement of the beveled face of the flange with the side or edge *c'* of 95 100 the rail.

the rail when passing curves, at which time the utility of the flange as a whole is most required.

We do not limit ourselves to forty-five degrees as the angle of the face a , although we consider this a suitable angle.

The wheels shown in the drawings are supposed to be mounted in bearings which have no provision for radial adjustment, so that when they are on a curve the axle will extend obliquely with relation to a radius of the curve. The described form of the wheel-flanges, however, causes the faces a of the flanges to bear on the edges c' of the rails in such manner that a line rr , which is a radius of the curve, will intersect the two portions of the wheel-flanges which bear on the rail edges $c' c'$, as shown in Fig. 2. Hence the

flanges bear on the edges of the rails in substantially the same way that they do when the so-called "radial" adjustment is provided.

We claim—

A car-wheel having a flange with a beveled outer face a and formed with a slight shoulder a' substantially at a right angle to the tread-surface of the wheel and intermediate the said tread-surface and beveled flange-face.

In testimony whereof we have affixed our signatures in presence of two witnesses.

HENRY F. SHAW.
GEORGE F. SHAW.
